CIRCUIT BREAKER

Joe Weber, Irwin, Pa., assignor to Westinghouse Electric & Manufacturing Company, East Pittsburgh, Pa., a corporation of Pennsylvania

Application March 19, 1942, Serial No. 435,367

21 Claims.

(Cl. 200—88)

This invention relates to circuit breakers and, more particularly, to circuit breakers of the type which are operated instantaneously on heavy overloads or short circuits and after a time delay on persistent overloads of lesser magnitude.

An object of the invention is to provide a circuit breaker having an improved current responsive trip device wherein a resistance connected in series with an electromagnet for tripping the breaker is controlled by a thermal element to control energization of the electromagnet and tripping of the breaker.

Another object of the invention is to provide a circuit breaker with an improved trip device wherein a thermal element deflects, when heated in response to overload currents, to reduce a resistance connected in series with the winding of the trip magnet, thereby causing increased energization of the magnet to trip the breaker.

Another object of the invention is to provide a circuit breaker having an improved trip device wherein the deflection of a thermal element in response to excessive current controls a variable regulator or a resistance to increase the energization of a trip electromagnet and effect tripping of the breaker.

Another object of the invention is to provide an improved circuit breaker wherein a trip magnet is energized under the control of a variable regulator or a resistance, which is varied by a bimetal element in accordance with the magnitude and duration of the overload current.

Another object of the invention is to provide a circuit breaker in accordance with the preceding paragraphs wherein means is provided for adjustably determining the initial resistance of the resistor to vary the operating point of the trip magnet.

Another object of the invention is to provide a circuit breaker with an improved trip device wherein a regulator or a resistance connected in series with a trip magnet is controlled by a thermal element to effect tripping of the breaker after a time delay on overloads below a predetermined value, and in which the magnet is effective to trip the breaker instantaneously on overloads above the predetermined value.

Another object of the invention is the provision of a circuit breaker with an improved trip device embodying a thermally responsive element heated in response to overload current of the circuit, and having means for varying the speed of response of the device in accordance with the magnitude of the overload current.

Another object of the invention is to provide a circuit breaker with an improved trip device which is simple in construction, reliable and efficient in operation, and inexpensive to manufacture.

5 The novel features that are considered characteristic of the invention are set forth in particular in the appended claims. The invention itself, however, both as to structure and operation, together with additional objects and advantages thereof, will be best understood from the following description of several embodiments thereof when read in conjunction with the accompanying drawing, in which:

Figure 1 is a vertical sectional view of a circuit breaker embodying the principles of the invention; and

Figs. 2 and 3 are fragmentary views of a circuit breaker embodying modified forms of the invention.

The circuit breaker illustrated in Fig. 1, with the exception of the trip device, is essentially the same as that disclosed in United States Patent No. 1,802,758, issued to H. D. Dorfman on April 28, 1931, and assigned to the assignee of the instant invention, and only a brief description of the structure of the circuit breaker will be given herein. For the specific details of construction, reference may be had to the patent referred to.

30 The circuit breaker comprises, generally, a base 1 and a cover 9 of molded insulating material, end terminals 11, a stationary contact 13, a movable contact 15, operating mechanism indicated generally at 17, a current-responsive trip device indicated at 19, and an arc extinguisher 21.

35 The movable contact 15 is secured to a resilient contact arm 27 which, in turn, is secured by suitable means to a channel-shaped frame 29 pivotally supported by means of a pivot pin 30 on a U-shaped main frame 31.

40 The operating mechanism 17 comprises a U-shaped operating lever 33 having an operating handle 35 secured to the outer end thereof and projecting through an opening 36 in the cover 9, a cradle 37, a toggle comprising a pair of toggle links 39 and 41, and a pair of overcenter springs 43 (only one of which is shown). The operating lever is pivotally mounted on pivot pins 34 supported in the sides of the frame 31, and the cradle 37 is pivoted on a pin 38 also supported in the frame 31. One end of the toggle link 39 is pivotally connected to the cradle 37 by a pin 40, and the toggle link 41 is pivotally connected to the free end of the channel-shaped

member 29 by means of a pin 42. The toggle links 39 and 41 are pivotally connected together by a knee pivot pin 44. The overcenter springs 43 are tensioned between the knee pin 44 of the toggle 39-41 and the outer end of the operating lever 33. The cradle 37 is provided with a latch end 45 with which a pivoted latch member 47 is adapted to cooperate to releasably restrain the cradle 37 in the position shown. The operating member 33 is provided with an extension 49 which is adapted to cooperate with the cradle 37 in order to relatch the cradle by manual movement of the handle 35 to the "off" position after the breaker has been tripped open.

When the latch member 47 is operated by the trip device 19 in a manner to be presently described, the cradle 37 is released and rotated in a clockwise direction by the overcenter springs 43. During this rotation, the line of action of the springs 43 changes to cause collapse of the toggle 39-41 and opening of the contacts 15-13.

Before the contacts may be closed, it is necessary to relatch the cradle 37 with the latch member 47. This is effected by moving the operating handle 35 in a counterclockwise direction, during which movement the extension 49 of the operating lever 33 engages and rotates the cradle 37 in the same direction to reengage the latch portion 45 of the cradle with the latch 59. The contacts can now be closed by moving the handle 35 and the operating lever 33 to the extreme right-hand position. This movement changes the line of action of the overcenter spring so as to straighten the toggle 39-41 and thus effect closing of the contacts.

The breaker may be opened manually by moving the handle 35 toward the left. During this movement, the line of action of the overcenter springs 43 is moved to the left of the pivot pin 43, causing the springs to exert a force on the knee of the toggle 39-41 in a direction to cause collapse of the toggle, which results in movement of the movable contact 15 to open position. The contacts are closed in the previously described manner.

The trip device 19 includes the latch member 47 pivotally mounted on a pivot 51 supported on ears 53 (only one being shown) formed on the support member 55. A spring 57 biases the latch member in latching direction. On the free end of the latch member 47 is mounted an armature 60 adapted to be attracted by an electromagnet 61 mounted on the support bracket 55. The electromagnet comprises a winding 63 and a core member 65, and is adapted to be energized in response to the current of the circuit. Also mounted on the support bracket 55 by means of an insulating button 97 is a variable regulator of any suitable type, such as a carbon pile 67. A bimetallic member 69 is supported on an angular bracket 71 secured to the conductor 20 by means of a screw 73, and extends outwardly therefrom adjacent one end of the resistance 67. An adjusting screw 75 having an insulating button 77 mounted on one end thereof bearing against the end of the carbon pile is locked in place on the bimetal element 69 by means of a lock nut 79. The purpose of the screw 75 is to communicate the deflecting movement of the bimetallic member 69 to the carbon pile 67 and also to provide a convenient means for adjusting the initial compression of the carbon pile. The conductor 20, which is formed as an extension of the terminal 11, is connected by means of a shunt conductor 81 of predetermined electrical resistance to the

conductor 83, and the conductor 83 is connected to the channel frame 29 by means of a flexible shunt conductor 85.

The circuit of the breaker extends from the left-hand terminal 11 through the conductor 20, the resistance shunt conductor 81, the conductor 83, flexible shunt conductor 85, channel member 29, resilient contact arm 27, movable contact 15, the stationary contact 13, the conductor 25 to the other terminal 11. The bimetal element 69, the winding 63 of the magnet 61 and the carbon pile 67 are electrically connected in series relation in a shunt circuit as follows: From the terminal 11 through the conductor 20, angle bracket 71, bimetallic element 69, a flexible wire 87, winding 63 of the electromagnet 61, a wire 89, through the carbon pile 67 and a wire 81 to the conductor 83, thus completing a shunt circuit in parallel with the shunt member 81.

When normal rated current flows through the circuit of the breaker, the resistance of the carbon pile 67 is of such value that current flow through the bimetallic element 69 and the magnet winding 63 is negligible, and, therefore, is insufficient to energize the winding 63 to cause operation of the latch member 47. Upon the occurrence of a persistent overload current, the resistance of the shunt conductor 81 forces an increased flow of current through the bimetal 69, the winding of the electromagnet 61 and the resistance 67. This results in heating the bimetal an amount determined by the value and duration of the overload current, and causes the bimetal to deflect in a direction to increase the compression of the carbon pile 67. The resistance of the carbon pile is thereby lowered, resulting in an increased flow of current through the winding 63 and the bimetal element 69. The increase in the value of current flowing through the bimetal element due to the decrease in resistance of the carbon pile 67 causes the bimetal to be heated at an increased rate, thereby producing a cumulative effect to increase the rate and extent of deflection of the bimetal element. Thus the time delay action of the trip device is less than the ordinary thermal trip device, and the time delay decreases at an accelerated rate as the magnitude of the overload current increases. When the current flow through the electromagnet 61 reaches a predetermined magnitude, the electromagnet attracts the armature 60 and causes the operating mechanism to open the contacts in the previously described manner.

By rotating the adjusting screw 75, the initial pressure on the carbon pile 67 may be increased or decreased, thus decreasing or increasing the initial resistance. This provides a convenient means for varying the operating point of the trip device. Upon the occurrence of overloads above a predetermined value or short-circuits, the excessive current energizes the magnet 61 sufficiently to cause instantaneous operation of the trip member 47 to release the operating mechanism. Obviously, by mounting the carbon pile 67 on the support 55 a greater or lesser distance from the base 7, the change in pressure on the carbon pile for a given deflection of the bimetal element may be varied.

According to the modification of the invention shown in Fig. 2, the bimetal element 69 may be provided with an auxiliary armature member 93 securely mounted on the bimetal adjacent the core member 65. The purpose of the auxiliary armature 93 is to provide for quicker tripping of the breaker for a given amount of heating of the

bimetal on intermediate overload currents below the previously mentioned predetermined value. When the bimetal element is heated in response to an overload current, it deflects toward the right and simultaneously increases the pressure on the carbon pile 67 and at the same time moves the armature 93 closer to the core of the magnet. This causes the electromagnet to exert a stronger pull on the armature 93 which tends to still further deflect the bimetal and thereby further decrease the resistance of the carbon pile. The rate of heating of the bimetal element is increased due to the decrease in resistance of the carbon pile and the increased pull of the magnet on the armature 93 due to the increased current flow through its winding and the decrease in air gap between the armature 93 and core 65 produces cumulative effects all tending to decrease the time delay action of the device in accordance with the magnitude of the current. The result is to increase the flow of current through the winding 63 and to increase the magnetic flux, and thus effect quicker tripping of the breaker for a given value of overload current than in the case of the original embodiment.

According to the modification of the invention illustrated in Fig. 3, the magnet winding 63 and the carbon pile 67 are electrically connected in parallel, and both are connected in series with the bimetal element 69 which is disposed to deflect, when heated, away from the carbon pile. Thus, under normal circuit conditions, the pressure exerted on the carbon pile by the bimetal element is at its maximum, and the resistance of the carbon pile is at its minimum, thereby limiting the value of current flowing through the winding 63. As the bimetal 69 is heated and deflects away from the carbon pile 67, the pressure thereon is reduced, thus increasing the resistance and causing an increased flow of current through the magnet winding 63. When the magnitude of the current flowing through the electromagnet reaches or exceeds a predetermined value, the electromagnet effects tripping of the breaker in the previously described manner.

Having described several embodiments of the invention in accordance with the patent statutes, it is to be understood that various changes and modifications may be made therein without departing from some of the essential features of the invention. It is, therefore, desired that the language of the appended claims be given as reasonably broad interpretation as the prior art permits.

I claim as my invention:

1. A circuit breaker comprising an operating mechanism for operating the breaker, a trip device comprising an electromagnet operable to cause operation of the breaker, a resistor electrically connected in series with said electromagnet, and a current-responsive member connected in series relation with said electromagnet and said resistor, said current-responsive member being operable in response to certain circuit conditions to decrease the resistance of the resistor and cause the electromagnet to trip the breaker.

2. A circuit breaker comprising an operating mechanism for causing automatic operation of the breaker, a trip device comprising an electromagnet operable to cause operation of said mechanism, a variable resistor for controlling the energization of said electromagnet, and thermally responsive means operable when heated in response to overload currents for varying the resistance of said resistor in accordance with the magnitude and duration of the overload current to vary the energization of the electromagnet.

3. A circuit breaker comprising relatively movable contacts, operating mechanism for said contacts, an electromagnet operable when energized a predetermined amount to cause opening of the contacts, a variable resistor for controlling the energization of said electromagnet, and a bimetallic element operable in response to overload currents to cause the resistor to increase the energization of the electromagnet and thereby effect opening of the contacts.

4. A circuit breaker comprising relatively movable contacts, operating mechanism for said contacts, a trip device comprising an electromagnet operable when energized by overload currents above a predetermined value to cause instantaneous opening of the contacts, a variable resistor connected in the circuit of the electromagnet for controlling the energization of said magnet, and a bimetallic element operable when heated by overload currents below said predetermined value to cause the resistor to increase the energization of the electromagnet in accordance with the magnitude and duration of the overload current.

5. A circuit breaker comprising relatively movable contacts, operating mechanism for said contacts, a trip device comprising electroresponsive means operable when energized a predetermined amount to cause opening of the contacts, a variable regulator for controlling the energization of the electroresponsive means, and thermally responsive means operable in response to overload currents for actuating the regulator in accordance with the magnitude and duration of the overload current.

6. A circuit breaker comprising relatively movable contacts, operating mechanism therefor, electroresponsive means operable when energized a predetermined amount to cause opening of the contacts, a variable regulator for controlling the energization of the electroresponsive means, thermally responsive means operable when heated in response to overload currents to actuate the regulator to increase the energization of the electroresponsive means an amount determined by the magnitude and duration of the overload current, and means for adjusting the regulator to vary the operating point of the electroresponsive means.

7. A circuit breaker comprising relatively movable contacts, operating mechanism for said contacts, a trip device comprising an electromagnet operable when energized a predetermined amount to cause opening of said contacts, a variable resistor for controlling the energization of the electromagnet, a bimetallic member operable when heated in response to overload currents for actuating the resistor to cause increased energization of the electromagnet in accordance with the magnitude and duration of the overload current, and means for adjusting the resistor to vary the initial resistance thereof.

8. A circuit breaker comprising relatively movable contacts, operating mechanism for said contacts, a trip device comprising an electromagnet operable when energized to cause opening of the contacts, a variable resistor for controlling the energization of said electromagnet, auxiliary magnetic means operable to vary the magnetic reluctance of said electromagnet, and a bimetallic element operable when heated in response to overload currents for varying the resistance of said resistor in accordance with the magnitude and duration of the overload current to vary the energization of the electromagnet.

to overload currents for simultaneously actuating the resistor to effect increased energization of the electromagnet and for actuating the auxiliary magnetic means to reduce the magnetic reluctance.

9. A circuit breaker comprising operating mechanism for causing automatic operation of the breaker, a trip device comprising an electromagnet operable to cause said mechanism to operate the breaker, a variable resistor for controlling the energization of said electromagnet, and a bimetallic element operable when heated in response to overload currents to increase the resistance of said resistor and cause increased energization of the electromagnet.

10. A circuit breaker comprising relatively movable contacts, operating mechanism for said contacts, a trip device comprising an electromagnet operable when energized a predetermined amount to cause opening of said contacts, a variable resistor for controlling the energization of said electromagnet, a bimetallic element operatively associated with said resistor and operable in response to overload currents to increase the resistance of said resistor to thereby increase the energization of the electromagnet, and adjustable means for adjustably determining the initial resistance of said resistor to vary the operating point of the electromagnet.

11. A circuit breaker comprising relatively movable contacts, operating mechanism biased to cause opening of said contacts, latch means for restraining said operating mechanism and operable to cause opening of said contacts, an electromagnet operable when energized a predetermined amount for operating said latch means, a variable resistor for controlling the amount of energization of said electromagnet, and a bimetallic element operable when heated in response to overload currents to decrease the resistance of the resistor thereby increasing the energization of the electromagnet.

12. A circuit breaker comprising relatively movable contacts, operating mechanism for said contacts, an armature operable to cause opening of said contacts, an electromagnet operable when energized a predetermined amount for operating said armature, a variable resistor comprising a carbon pile for controlling the amount of energization of said electromagnet, a bimetallic element operable when heated in response to current for actuating said carbon pile to reduce the resistance thereof to thereby increase the energization of the electromagnet and cause said electromagnet to operate the armature.

13. A circuit breaker comprising relatively movable contacts, operating mechanism for said contacts, an armature operable to cause opening of the contacts, an electromagnet operable when energized a predetermined amount to operate said armature, a variable resistor comprising a carbon pile for varying the energization of said electromagnet, a bimetallic element operable when heated in response to current to reduce the resistance of said carbon pile to thereby increase the energization of the electromagnet and cause said electromagnet to operate the armature, and adjustable means for determining the initial resistance of the carbon pile to vary the operating point of the electromagnet.

14. A circuit breaker comprising relatively movable contacts, operating mechanism for said contacts, an electromagnet including a movable armature operable to cause opening of the contacts, said electromagnet being operable when

energized a predetermined amount to operate the armature, a variable resistor comprising a carbon pile operable to vary the energization of the magnet, an auxiliary armature operable to vary the reluctance of the magnet, and a bimetallic element operable when heated in response to current to simultaneously operate the carbon pile and the auxiliary armature to simultaneously increase the energization of the electromagnet and reduce the magnetic reluctance.

15. A circuit breaker comprising relatively movable contacts, operating mechanism therefor, an electromagnet including an armature operable to cause opening of said contacts, a variable resistor for controlling the energization of said electromagnet, an auxiliary armature operable to vary the magnetic air gap of the electromagnet, and a bimetallic element operable when heated in response to current to actuate the variable resistor and the auxiliary armature to simultaneously increase the energization of the electromagnet and reduce the magnetic air gap.

16. A circuit breaker comprising relatively movable contacts, operating mechanism therefor, a trip device operable to cause opening of the contacts, said trip device comprising a bimetal element heated in response to the current of the circuit and operable to cause operation of the trip device, a variable resistance connected in series relation with said bimetal element in the circuit controlled by the breaker, said bimetal element deflecting when heated to reduce the resistance of the variable resistance thereby increasing the heating of the bimetal element.

17. A circuit breaker comprising an operating mechanism for operating the breaker, a trip device comprising an electromagnet operable to cause operation of the breaker, a variable resistance electrically connected in the energizing circuit of said electromagnet, a bimetal element at all times connected in series relation with said variable resistance and heated in response to the current of the circuit of the electromagnet, and means including said bimetal element for varying the resistance of said variable resistance.

18. A circuit breaker comprising relatively movable contacts, operating mechanism for said contacts, a trip device comprising an electromagnet operable when energized by overload currents above a predetermined value to cause instantaneous opening of the contacts, a variable resistor connected in the circuit of the electromagnet for controlling energization of said magnet, and a bimetal element connected in series with a parallel connection of said variable resistor and the electromagnet, said bimetal element being heated in response to the current in the circuits of the electromagnet and said variable resistor, said element being deflectable in response to predetermined heating of said element to operate the resistor and vary the resistance of said variable resistor.

19. A circuit breaker comprising relatively movable contacts, operating mechanism for said contacts, a trip device including an electromagnet having an armature operable to cause opening of the contacts, a variable resistance for controlling the energization of said electromagnet, a bimetal element deflecting when heated in response to overload currents in a direction to actuate the variable resistance to thereby cause increased energization of the electromagnet, and an auxiliary armature movable toward the electromagnet upon deflection of the bimetal ele-

ment, said auxiliary armature exerting a force on the bimetal element tending to deflect said element in the same direction as the heating action.

20. A circuit breaker comprising relatively movable contacts, operating mechanism for said contacts, an electromagnet including a movable armature operable to cause opening of the contacts, said electromagnet being operable when energized a predetermined amount to operate the armature, a variable resistor comprising a carbon pile operable to vary the energization of the electromagnet, an auxiliary armature operable to effect increased energization of the electromagnet, and a bimetal element operable when heated in response to current to simultaneously

operate the carbon pile and to move the auxiliary armature closer to the electromagnet to thereby effect increased energization of said magnet.

21. A circuit breaker comprising relatively movable contacts, operating mechanism therefor, an electromagnet including an armature operable to cause opening of said contacts, a variable resistor for controlling the energization of said magnet, a bimetal element operable when heated 10 in response to current to actuate the variable resistor to cause increased energization of the electromagnet, and an auxiliary armature movable by the bimetal element and operable by the electromagnet to effect additional increase in the energization of said magnet.

JOE WEBER.
